(57) CLAIM

The ornamental design for pages for notebook, as shown and described.

DESCRIPTION

The patent or application file contains at least one drawing executed as a photograph and/or in color. Copies of this patent or patent application with photographs and color drawings will be provided by the Office upon request and payment of the necessary fee.

FIG. 1 is a perspective view of the pages for notebook showing my new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines shown in the drawings (sometimes shown in red font) depict environmental subject matter only and form no part of the claimed design.
